UNITED STATES PATENT OFFICE.

DITON H. ABNEY, OF KANSAS CITY, MISSOURI.

ADJUSTABLE COUPLING FOR SEWING-MACHINE OR OTHER ROUND BELTS.

SPECIFICATION forming part of Letters Patent No. 691,884, dated January 28, 1902.

Application filed May 9, 1901. Serial No. 59,365. (No model.)

To all whom it may concern:

Be it known that I, DITON H. ABNEY, a citizen of the United States, residing at Kansas City, in the county of Jackson and State of Missouri, have invented certain new and useful Improvements in Adjustable Couplings for Sewing-Machine or other Round Belts, of which the following is a specification.

My invention relates to an adjustable coupling for sewing-machine and other round belts; and my object is to produce a device of this character whereby an unskilled person can easily and quickly tension the belt as desired.

15 The invention consists, essentially, in a coupling comprising two members detachably connected together and mounted on the ends of a belt, at least one of said members being adapted when turned in the proper direction 20 to synchronously advance upon the belt and pare from its end an amount of material proportionate to such advance, and thereby maintain its proper relative position with respect to the companion member.

25 With the above object in view the invention further consists in certain novel and peculiar features of construction and combinations of parts, as hereinafter described and claimed, and in order that it may be fully 30 understood reference is to be had to the accompanying drawings, in which—

Figure 1 is a side elevation showing the ends of a round belt secured together by a coupling embodying my invention. Fig. 2 is 35 a perspective view showing the progressive or cutting member as advanced by a wrench or key upon the belt and also shows projecting from said member a strip as pared from the end of the belt. Fig. 3 shows a longitudinal section of said adjustable member of the coupling detached from the belt. Fig. 4 is a cross-section taken on line IV IV of Fig. 3.

Referring to the drawings in detail, where 45 like reference characters designate corresponding parts, 1 designates an ordinary round belt, of leather or equivalent material—such, for instance, as a sewing-machine belt.

2 designates one of the members of my im- 50 proved coupling, the same being of cylindrical form, preferably, and reliably secured upon one end of the belt in any suitable or

preferred manner, said member by preference terminating in a hook 3. 4 designates the other member of the coupling, the same being also 55 of cylindrical form in cross-section and mounted upon the opposite end of the belt and terminating, preferably, in loop 5 for engagement with hook 3. Member 4 is internally screw-threaded, as shown at 6, in order that 60 when turned in the proper direction upon the belt it shall advance thereon, cutting its mating thread in the belt in an obvious manner, it being understood, of course, that the front end of said member is preferably flared or 65 sharpened, as at 7, so as to facilitate this operation.

8 designates a cutting blade or knife projecting radially of member 4 to the center of the same, and said blade or knife may be 70 formed integral with the member or secured therein in any suitable manner, being preferably screwed therein, as shown at 9, though it may be riveted in place, if desired. It extends inward to the center of the member in 75 order that it may cut or pare to the center of the belt and is of course pitched at an angle to the end of the belt, the pitch preferably corresponding to that of the threads in order that it shall cut or pare material from the end 80 of the belt proportionate to the advance thereon of the member, it being obvious that the pitch or inclination of the blade or knife determines the thickness of said strip and that as the knife travels spirally said strip emerges 85 from the front end of the member in the form of a spiral shaving, as shown at 10, the same being readily detached when the desired adjustment of the member is attained by a slight pull; this pull resulting in drawing it against 90 the edge of the knife, as will be readily understood.

To advance member 4 upon the belt, it is first disconnected from the companion member 2, and because the belt presents a small 95 surface to be gripped it is desirable to use a key or wrench, as at 11, to engage the loop and give the operator the desired purchase or leverage in turning it, and owing to the flexibility of the belt it is also desirable to use 100 a pair of pliers to grip the belt a slight distance in advance of the member and hold it rigid while the key or wrench is being turned, or the belt may be secured in a vise to hold

it during such operation; but as the pliers and vise form no part of the invention and may be of any suitable type they are not herein shown and described. Furthermore, the 5 member may be screwed upon the belt by means of a small wire rod inserted through loop 5 to get the desired leverage as a substitute for the key or wrench 11 shown. It is also obvious that the hook 3 and loop 5 are 10 not indispensable, as a different type of connection for detachably uniting the members may be employed without affecting the essential parts of the coupling, the same comprising a tubular internally-threaded member 15 and a knife carried thereby, substantially as shown and described.

As is well known, sewing-machine operators frequently experience considerable annoyance and trouble in tensioning the belts of 20 their machines. Usually the connection is by means of a wire link engaging holes in the ends of the belt. With this connection the only method of tensioning after bending the loop so as to disconnect it at one end from the 25 belt is to cut off a portion from the end of the belt, make a new perforation at what is considered the proper point, rethread the link therethrough, and bend it back to its original shape. The amount cut off under ordinary 30 conditions is by guess. If too much is removed, the belt is ruined for that machine unless an additional piece be spliced on, an operation usually beyond the skill of the operator. If too little is cut off, then the operation 35 just described must be repeated, and it sometimes is necessary to repeat this operation several times, as it is advisable usually to err on the safe side by cutting off a fraction less than what is deemed the true amount, as 40 a mistake on the other side is irreparable. With my invention this difficulty and trouble are entirely eliminated, as the adjustment by member 4 may be made almost imperceptible. Another difficulty with shortening the 45 belt in the old way is that the operator must cut off an amount at least equal to the diameter of the hole or slit made to receive the link; but where the adjustment should be less than that distance it is obvious that it is 50 impossible to retension the belt.

This improved coupling is intended to be used in connection with lathe-belts and, in fact, in various other connections, though it is designed especially for use upon sewing- 55 machines.

From the above description it will be apparent that I have produced an adjustable coupling for belts which embodies the features of advantage enumerated as desirable 60 in the statement of invention, and it is to be understood that while I have illustrated and

described its preferred embodiment I reserve the right to make such changes in the form, proportion, detail construction, and arrangement of the parts as shall not involve a departure from the spirit and scope of the invention. 65

Having thus described the invention, what I claim as new, and desire to secure by Letters Patent, is— 70

1. In a device of the character described, an internally-threaded tubular member to be screwed upon the end of the belt and provided with a knife or blade to engage and pare off the end of the belt. 75

2. In a device of the character described, an internally-threaded member to be screwed upon the belt and a knife projecting radially thereof and arranged at an angle approximating that of said threaded surface. 80

3. In a device of the character described, an internally-threaded member to screw upon the end of the belt and provided at its rear end with a loop, and provided also forward of said loop with an inwardly-projecting knife 85 having its sharp edge presented toward the end of the belt.

4. In a device of the character described the combination of a belt, and a coupling comprising a pair of members mounted on the 90 ends of the belt and detachably connected together, one of said members being screwed upon the end of the belt and provided with a knife or blade to pare off the end of the belt as said member is screwed thereon. 95

5. In a device of the character described, the combination of a belt, and a coupling consisting of a pair of members mounted on the ends of the belt, one of said members being screwed upon the belt and provided with an 100 inwardly-projecting knife to pare off the end of the belt as said member is screwed thereon, one of said members being provided with a hook and the other with a loop detachably engaging the hook, substantially as described. 105

6. In a device of the character described, the combination of a belt, and a coupling consisting of a pair of members mounted on the ends of the belt and detachably connected together, one of said members being internally 110 threaded and having its front end beveled to flare as at 7, and provided with an inwardly-projecting knife to pare off the end of the belt as said member advances thereon, substantially as described. 115

In testimony whereof I affix my signature in the presence of two witnesses.

DITON H. ABNEY.
